DESIGN FOR A RECEPTACLE SEALING CAP

Edward H. Fabrice, Chicago, Ill.

Application June 22, 1938, Serial No. 77,993

Term of patent 7 years

To all whom it may concern:

Be it known that I, Edward H. Fabrice, a citizen of the United States, resident of Chicago, in the county of Cook, State of Illinois, have invented a new, original, and ornamental Design for a Receptacle Sealing Cap, of which the following is a specification, reference being had to the accompanying drawing, forming a part thereof, wherein a perspective view of a receptacle sealing cap embodying the design of my invention as viewed from the front thereof is shown; the side of the cap diametrically opposite to that shown being identical in appearance.

I claim:

The ornamental design for a receptacle sealing cap, as shown and described.

EDWARD H. FABRICE.
